(57) **CLAIM**

We claim the ornamental design for an airframe, as shown and described.

DESCRIPTION

FIG. 1 is a front perspective of an airframe, of my new design;

FIG. 2 is a bottom perspective of an airframe, of my new design;

FIG. 3 is a top elevational view of an airframe, of my new design;

FIG. 4 is a bottom elevational view of an airframe, of my new design;

FIG. 5 is a left elevational view of an airframe, of my new design;

FIG. 6 is a right elevational view of an airframe, of my new design;

FIG. 7 is a front plan view of an airframe, of my new design; and,

FIG. 8 is a rear plan view of an airframe, of my new design. The broken lines in the drawings represent unclaimed environmental subject matter and form no part of the claim.

1 Claim, 8 Drawing Sheets
